(57) **CLAIM**

The ornamental design for a wall charger adapter, as shown and described.

DESCRIPTION

FIG. 1 is a first perspective view of a wall charger adapter showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an exploded perspective view thereof.

The broken lines shown in the drawings depict portions of the wall charger adapter in which the design is embodied that form no part of the claimed design.
